UNITED STATES PATENT OFFICE

121,022

DESIGN FOR A PHOTOGRAPHIC CAMERA CASE

Jean O. Reinecke, Chicago, Ill., assignor to The Bell & Howell Company, Chicago, Ill., a corporation of Illinois

Application April 10, 1940, Serial No. 91,581

Term of patent 14 years

To all whom it may concern:

Be it known that I, Jean O. Reinecke, a citizen of the United States, residing at Chicago, in the county of Cook and State of Illinois, have invented a new, original, and ornamental Design for a Photographic Camera Case, of which the following is a specification, reference being had to the accompanying drawings, forming a part thereof.

In the said drawings

Figure 1 is a side elevation of a photographic camera case, showing my new design;

Figure 2 is an opposite side elevation of the same;

Figure 3 is a top plan view of the same;

Figure 4 is a front elevation of the same; and Figure 5 is a rear elevation of the same.

I claim:

The ornamental design for a photographic camera case, as shown.

JEAN O. REINECKE.
